UNITED STATES PATENT OFFICE.

ROBERT HENRY, OF PUEBLO, COLORADO.

ELECTRIC-LINE INSULATOR.

No. 922,477.

Specification of Letters Patent.

Patented May 25, 1909.

Application filed October 5, 1908. Serial No. 456,198.

To all whom it may concern:

Be it known that I, ROBERT HENRY, a citizen of the United States, and a resident of Pueblo, in the county of Pueblo and State 5 of Colorado, have invented a new and useful Improvement in Electric-Line Insulators, of which the following is a specification.

My invention relates to improvements in the method of insulating electric lines on 10 poles in which the insulating material is attached to the usual pin and a peculiar form is given for holding the line firmly in position; and the objects of my invention are; first, to provide a means for holding the line 15 or cable in position without the use of binding wires; second, to provide a rapid means of attaching the line to the insulator; third, to furnish additional strength in the insulator; and fourth, to provide such insulator 20 with means of ready repair in case of accident or quick facilities of change of line. I attain these objects by the mechanisms illustrated in the accompanying drawings in which,—

25 Figure 1 is a perpendicular sectional view; Fig. 2 is a plan view with broken section of one arm; Fig. 3 is a perspective view; and Fig. 4 is a side view of the locking pin.

Similar numerals refer to similar parts 30 throughout the several views.

The ordinary pin or post 1 with threads 8 is used. A cap 2, threaded to fit post 1, is constructed of any well known insulating material, glass being preferred. The upper 35 portion of cap 2 is threaded as at 7 down to a point opposite the threads on 1 and is made in one solid piece covering the top of 1, the cap 2 being threaded interiorly to fit post 1 and exteriorly as stated. A locking cap 3 40 having interior threads 7 fitting exterior threads on 2 is constructed with extending bosses 13 and each of said bosses has a lateral slot 5 and a perpendicular slot 4 so placed that the slot 5 extends a required 45 distance in past the interior side of 4 forming pocket 4^a. Said locking cap is also provided with extended, flanged base 12, and so adjusted as to leave a space 14 between 2 and lower parts of 3. Locking key 9, Fig. 50 4, is provided which fits into perpendicular slot 4. At the lower end of locking key 9 angular space 10 is provided the use of which is explained further on. The line or wire is represented by 11.

The device being adjusted upon pin or post 55 1 a wire or line 11 is passed into slot 5 and locking pin 9 is inserted in slot 4 and firmly driven in and thereby kinks the line or wire 60 11 as shown at 11^a. In this form the insulation is protected additionally from moisture 65 by the space 14 which completely encircles 2 and the wire 11 by the clamp or kink at 11^a is firmly held in position.

If desired two wires may be placed on each insulator, one in each of the slots 5, or upon 70 accident or injury to one of the bosses the other is available for use in repairing. The pull of the line or wire upon the insulator is made by the construction to bear equally upon that portion of the pin 1 included in the insulator. The notch 10 in locking pin 9 is provided as a means of removing pin when desired by use of a punch through space 14.

I claim:

1. In an electric line insulator of the character described, an interior screw threaded locking cap fitted on interior insulation, exterior bosses on said locking cap each having a perpendicular slot, a pin fitted in said perpendicular slot having a notch in the lower 80 end, a lateral slot in each of said bosses intersecting said perpendicular slot and making pocket on interior side of said perpendicular slot, flanged circular base on said locking cap, a space between said flanged 85 circular base and extended portion of interior insulation, all substantially as set forth.

2. In an electric line insulator of the character described, an interior screw threaded locking cap fitted on interior insulation, exterior bosses on said locking cap each having a perpendicular slot, a pin fitted in said perpendicular slot having a notch in the lower 90 end, a lateral slot in each of said bosses intersecting said perpendicular slot and making pocket on interior side of said perpendicular slot, flanged circular base on said locking cap, a space between said flanged 95 circular base and extended portion of interior insulation, interior insulation screw threaded on interior and screw threaded on exterior to fit interior of said locking cap, all substantially as set forth.

ROBERT HENRY.
